HANDLE APPARATUS

James W. Serio, Hillcrest Road, Elmira, N.Y. 14903
Filed Feb. 15, 1965, Ser. No. 432,517
8 Claims. (Cl. 294—31.2)

The present invention relates to new and novel handle apparatus, and more particularly to handle apparatus adapted to be associated with containers.

The handle apparatus of the present invention is especially adapted for use with containers of the type which open at the upper end thereof and which are provided with an unusual external contoured configuration. The type of handle according to the present invention is also provided with contoured surfaces which are adapted to snugly engage the outer surface of the container to thereby present a very attractive finished product.

The handle portion which is manually grasped and which engages the outer surface of the container is associated with an engaging means in the form of an elongated band of flexible material which is separate from the container and which is adapted to be clamped about the container.

Clamping means is provided whereby upon assembly, the band may be readily clamped about the container and very tightly secured in operative position so that it will not slip off. To assist in this feature of the invention, the container may be provided with a peripheral recess therearound.

The clamping means is initially engaged with the end portions of the band for clamping the band in position. The manual graspable handle portion is provided with a cavity within which the opposite end portions of the engageable band and the clamping means are adapted to fit and be secured in place by a suitable means such as an adhesive or the like.

This over-all arrangement is particularly useful with contoured containers having correspondingly contoured handle portions which fit against the rather unusual shape of the container in a proper manner in only one relative position of the handle with respect to the container. This is to be contrasted with the type of an arrangement wherein the container has an absolutely flat surface and the handle may have a correspondingly flat surface which might fit the container in any relative position of the handle.

The end portions of the band and the clamping means fit within a cavity provided in the manually graspable part of the handle and are secured therein so as to be completely hidden from view thereby presenting a very neat external appearance such that after assembly no moving parts, holes, screws and the like are visible or exposed in any manner.

A further advantage of the arrangement of the present invention is that it enables the handle mechanism to be assembled in a most simple and effective manner which is virtually foolproof, thereby considerably reducing the time and effort required in assembling the apparatus on an associated container.

The clamping means itself is also provided with a bore having a flared portion which facilitates entry of the end portions of the band therein thereby enabling more ready assembly of the apparatus.

In one modification of the invention, detent means is provided between the end portions of the band and the clamping means to prevent the band from being released from proper tension about the associated container once the clamping means has been rotated with respect to the end portions of the band. Means is also provided in this modification for urging the opposite ends of the band outwardly into operative position.

2

In another modification of the invention, the opposite end portions of the band are provided with ears which are interengageable to provide a predetermined spacing of the end portions of the band and preventing the end portions of the band not only from collapsing inwardly toward one another but also limiting inward or outward bending of the ears in a direction longitudinally of the bore of the associated clamping means.

An object of the present invention is to provide new and novel handle apparatus which is particularly useful with handles which are contoured to fit snugly against an unusually shaped container and wherein the handle apparatus is adapted to be mounted in a predetermined relationship to the container.

Another object of the invention is to provide handle apparatus which in its assembled relationship presents a very neat external appearance, with no movable parts, holes, screws and the like exposed to view.

Still another object of the invention is the provision of handle apparatus which is capable of being very securely attached to an associated container.

A further object of the invention is to provide handle apparatus which may be quickly and easily assembled in a relatively foolproof manner on a container.

Yet another object of the invention is to provide handle apparatus which is quite simple and inexpensive in construction, and which is quite rugged and effective in use.

Other objects and many attendant advantages of the invention will become more apparent when considered in connection with the specification and accompanying drawings, wherein:

FIG. 1 is a top perspective view of a container with the handle apparatus of the present invention mounted thereon;

FIG. 2 is a sectional view taken substantially along line 2—2 of FIG. 1 looking in the direction of the arrows;

FIG. 3 is a sectional view taken substantially along line 3—3 of FIG. 2 looking in the direction of the arrows;

FIG. 4 is a sectional view taken substantially along line 4—4 of FIG. 2 looking in the direction of the arrows;

FIG. 5 is an exploded perspective view illustrating the manner in which certain components of the assembly are interengageable with one another;

FIG. 6 is a sectional view taken substantially along line 6—6 of FIG. 4 looking in the direction of the arrows;

FIG. 7 is a top perspective view of a container having a modified form of handle apparatus associated therewith;

FIG. 8 is a sectional view taken substantially along line 8—8 of FIG. 7 looking in the direction of the arrows;

FIG. 9 is a sectional view taken substantially along line 9—9 of FIG. 8 looking in the direction of the arrows;

FIG. 10 is a sectional view taken substantially along line 10—10 of FIG. 8 looking in the direction of the arrows; and

FIG. 11 is a exploded top perspective view of certain components of the assembly illustrating the manner in which they are assembled with respect to one another.

Referring now to the drawings wherein like reference characters designate corresponding parts throughout the several views, a first modification of the invention is illustrated in FIGS. 1—6 inclusive. As seen in these figures, a container is indicated generally by reference numeral 20 and may be of any particular construction as for example formed of ceramic material and the like. The container includes an upwardly tapered side wall portion 22 which joins with a peripherally extending recess portion 24 as seen particularly in FIG. 2 which in turn joins with an upper outwardly flared side wall portion 26. The container is open at the upper portion thereof as indicated by reference numeral 28, and a pouring spout portion 30 is formed integral with the upper wall portion 26.

The handle means itself is indicated generally by reference numeral 34 and may be formed of a suitable material such as plastic and the like which is a good heat insulator so as to protect the hand of the user when handling hot liquids for example. This handle means includes a manually graspable portion 36 which may be contoured so as to easily fit within the palm of the hand, and an upper portion 38 is provided which terminates in upper and lower end surfaces 40 and 42 respectively which are adapted to fit snugly against the outer surface of the associated container. These upper and lower end surfaces are joined by side end surfaces 44 as particularly seen in FIG. 5 for example, these surfaces 44 being normally spaced from the associated container.

The terminal end of upper portion 38 of the handle means is provided with a cavity 48 for receiving other components of the handle assembly, and an integral tapered projection 50 extends into the central part of cavity 48 for a purpose hereinafter described.

The engaging means comprises an elongated flexible band 54 formed of a suitable material such as aluminum or the like, this band including portions 56 and 58 of reduced width adjacent the opposite ends thereof and terminating in opposite end portions 60 and 62 of the same width as portions 56 and 58 respectively. End portions 60 and 62 extend laterally outwardly away from the adjacent portions of the band as seen in FIG. 5 and approximately perpendicular to the associated adjacent portions. These end portions are provided with ears 64 and 66 respectively which are formed at the terminal ends of the end portions and extend substantially perpendicularly from the associated end portions. Ears 64 and 66 are provided with integral struck-out portions 68 and 70 which serve as detent means as hereinafter described.

The clamping means of the assembly is indicated generally by reference numeral 74, this clamping means being formed of a suitable lightweight material such as plastic or the like and comprising an annular member having a plurality of longitudinal grooves 76 formed on the outer surface thereof for a purpose hereinafter described.

Clamping member 74 has a bore formed therethrough, this bore including a tapered portion 80 at one end thereof to facilitate entry of the opposite end portions of the band within the bore. The bore also includes a pair of cam surfaces indicated generally by reference numerals 82 and 84 as seen particularly in FIG. 4. These cam surfaces present inwardly facing surfaces which are disposed eccentrically with respect to the longitudinal axis x-x of the bore. That is to say, cam surface 82 slopes from a low point 82' to a high point 82'', the high point 82'' of this surface being closer to the axis x-x than point 82'. In a like manner, cam surface 84 slopes from a low point 84' to a high point 84'', point 84'' being spaced closer to the axis x-x than is the point 84'.

Clamping means 74 also includes a second pair of cam surfaces indicated generally by reference numerals 90 and 92 respectively, this pair of cam surfaces being formed on the outer end portion of the clamping means. Cam surface 90 slopes from a low point 90' to a high point 90'', point 90'' being spaced outwardly of point 90' in a direction extending longitudinally of the longitudinal axis of the clamping means. In a like manner, cam surface 92 slopes outwardly from a low point 92' to a high point 92'', point 92'' being spaced outwardly of point 92' in a direction extending parallel with the longitudinal axis of the clamping means.

Cam surface 90 is provided with a plurality of detent notches 94 of substantially V-shaped cross sectional configuration, and cam surface 92 is provided with a corresponding plurality of V-shaped detent notches 96. It will be noted that these notches extend in an angular relationship such that they will be adapted to engage the detent portions 68 and 70 of ears 60 and 66 respectively

as the ears are rotated with respect to the clamping means.

When assembling the handle apparatus shown in FIGS. 1 through 6, inclusive, the band 54 is first placed about 5 the peripheral recess portion of the container and the opposite end portions are moved toward one another so that they can be slipped into the bore provided through the clamping means 74. The opposite end portions 60 and 62 are extended through the bore until the ears 64 10 and 66 thereof extend beyond the end of the bore and onto cam surfaces 90 and 92 respectively as illustrated in FIGS. 3 and 4. When the ears are initially placed in this position, they will be disposed such that they are at the low points on each of the cam surfaces 82, 84, 90 and 92. 15 At this stage of the operation, the band is still rather loosely fitted about the associated container. The clamping means is then rotated with respect to the associated end portions of the band whereupon the inwardly facing cam surfaces 82 and 84 will move the end portions of the band toward one another which of course will tend to tighten the band about the container and simultaneously with such action the cam surfaces 90 and 92 will also pull the end portions of the band away from the container due to the interaction of these cam surfaces with 20 the ears 64 and 66 thereby further producing a tightening 25 ing action of the band.

The clamping means is rotated until the opposite end portions of the band are exposed at the high points of 30 the two cam surfaces or until no further rotation of the clamping means is possible due to the fact that the band may be very tightly clamped on the container. The detent means comprising the struck-out portions 68 and 70 and the detent notches 94 and 96 will prevent the clamping means from backing off from this tightened position.

35 A suitable adhesive substance such as epoxy resin or the like is then disposed in the longitudinal groove 76 in the outer surface of the clamping means, and the clamping means along with the opposite end portions of the band are placed within the cavity 48 of the handle by 40 pushing the handle into the operative position seen in FIGS. 1, 2 and 3. The clamping means is snugly received within cavity 48, and the adhesive substance will serve to permanently secure the clamping means within the cavity of the handle thereby securely holding the handle apparatus in the operative final position.

45 As the handle means is pushed into the position shown in FIGS. 2, 3 and 4, the central projection 50 of the handle will be received between the opposite end portions 60 and 62 and will maintain them in the desired operative 50 relationship. The tapered outer surface of projection 50 will enable it to be readily moved into operative position and serve to force the opposite end portions 60 and 62 outwardly into the desired relationship.

55 After so assembling the handle apparatus, it is merely necessary to dry the adhesive substance whereupon the completed finished structure is provided.

Referring now to FIGS. 7 through 11 inclusive, a modified form of the invention is illustrated. The container means is indicated generally by reference numeral 120 and may be identical with that shown in FIG. 1. This container means also includes an upwardly tapered side wall portion 122 which joins with a peripheral recess portion 124 which in turn joins with an upper outwardly flared side wall 126. The container is open at the upper end 128 thereof, and an integral pouring spout 130 is provided.

The handle means 134 is also very similar to the handle means previously described and includes a manually graspable contoured portion 136 which is formed integral with an upper part 138 which terminates in an upper end surface 140 and a lower end surface 142, these end surfaces being adapted to fit snugly against the associated side walls of the container.

The upper and lower surfaces 140 and 142 are joined 75 by side surfaces 144 which are normally spaced from

the container. A cavity 148 is provided in the end of the upper portion 138, the only difference in this particular handle means construction being that no projection is provided in the recess in the handle means.

The engaging means in this form of the invention comprises an elongated flexible band 150 formed of a suitable material such as aluminum or the like, the band including portions of reduced width 152 and 154 adjacent the opposite ends thereof and terminating in opposite end portions 156 and 158 which include integral ear portions 169 and 162 respectively which extend substantially perpendicularly from the adjacent end portions. The end portions also extend substantially perpendicularly from the portions 152 and 154 respectively.

End portions 156 and 158 are provided with integral screw thread means 156' and 158' therein for cooperating with the clamping means as hereinafter described.

The ears 160 and 162 are interengageable with one another as seen most clearly in FIGS. 9, 10 and 11, such interengagement serving to maintain these opposite end portions in predetermined spaced relationship as seen in FIG. 9 and also preventing inward or outward collapsing of the end portions when the apparatus is being assembled.

The clamping means is indicated generally by reference numeral 170 and comprises an annular member formed of plastic or the like having longitudinal grooves 172 formed in the outer surface thereof. The clamping means is provided with a bore formed therethrough, this bore including a first tapered portion 176 which is flared outwardly toward the associated end of the clamping member so as to facilitate entry of the opposite end portions of the band there within. The bore also includes a surface 178 having integral screw thread means formed therein adapted to cooperate with screw threaded portions of the opposite end portions of the band.

When assembling this form of the apparatus in operative position, the band is first disposed about the outer periphery of the container adjacent the recess portion 124 thereof, and the opposite end portions are moved into the relationship seen most clearly in FIGS. 9 and 11. The clamping means is then threaded onto the opposite end portions of the band into the operative position shown in FIG. 9. As the clamping means is threaded into position, the inner edge portion 180 thereof which is formed on a radius will engage the outer surfaces of the container and pull the end portions of the band away from the container to tighten it securely about the container. When the clamping means has been rotated with respect to the end portions of the band so as to tightly clamp the band about the container, the clamping means along with the end portions of the band are inserted within the cavity 148 provided in the handle means. As in the previous modification, a suitable adhesive substance such as epoxy resin is disposed within the longitudinal grooves 172 for securely and permanently retaining the apparatus in the assembled relationship.

It is apparent from the foregoing that there is provided according to the present invention new and novel handle apparatus which is particularly useful with unusually contoured containers and wherein the handle means is adapted to be mounted in a predetermined relationship on the container, the handle means generally being similarly contoured. The finished handle apparatus presents a very neat external appearance wherein there are no movable parts, holes, screws and the like exposed to view. The handle apparatus is adapted to be very securely clamped to and secured on a container and may be assembled in a substantially foolproof manner in a short amount of time. The over-all arrangement is quite simple and inexpensive in construction, yet is quite rugged and effective in use.

As this invention may be embodied in several forms without departing from the spirit or essential characteristics thereof, the present embodiment is therefore illustra-

tive and not restrictive, and since the scope of the invention is defined by the appended claims, all changes that fall within the metes and bounds of the claims or that form their functional as well as conjointly cooperative equivalents are therefore intended to be embraced by those claims.

I claim:

1. Handle apparatus comprising engaging means having opposite outwardly extending end portions, clamping means having a bore formed therethrough, said opposite end portions of said engaging means being received within said clamping means and extending through said bore and in engagement therewith, the wall of said bore defining a pair of inwardly facing cam surfaces, each of said cam surfaces defining a surface eccentric to the axis of said bore, said cam surfaces being engageable with the opposite end portions of said engaging means for clamping the engaging means tightly about an associated container upon relative rotation of said clamping means with respect to said end portions of the engaging means.

2. Handle apparatus comprising engaging means having opposite end portions, clamping means having a bore formed therethrough, said opposite end portions being received within said bore, said clamping means defining an outer surface and a pair of opposite end surfaces, one of said opposite end surfaces defining a pair of cam surfaces, each of said cam surfaces sloping from a low point to a high point toward the outermost end of said clamping means, said opposite end portions of the engaging means including surfaces in engagement with said cam surfaces.

3. Apparatus as defined in claim 2 wherein each of said cam surfaces has detent means formed thereon, the adjacent associated surfaces of the opposite end portions having cooperating detent means thereon for preventing relative rotation of said opposite end portions with respect to said clamping means in one direction.

4. Handle apparatus comprising engaging means including an elongated flexible band adapted to engage the outer periphery of a container, said band including opposite end portions extending laterally outwardly of the adjacent band portions, clamping means comprising a member having a bore formed therethrough, said opposite end portions extending through said bore and having in engagement therewith, the wall of said bore defining first cam means eccentric to the axis of said bore, one end portion of said clamping means defining cam means extending longitudinally of the axis of said bore, said opposite end portions engaging said first cam means including terminal ends engaging said second cam means whereby upon relative rotation of said clamping means with respect to said opposite end portions, the engaging means is clamped tightly about an associated container.

5. Apparatus as defined in claim 4 wherein one of said second cam means and the associated terminal end of an opposite end portion have interengageable detent means for preventing relative rotation between said clamping means and said opposite end portions in one direction of rotation.

6. Handle apparatus comprising engaging means including a band having separate opposite end portions extending laterally outwardly of the adjacent band portions, clamping means having a bore therein, said opposite end portions of the band being received within said bore, said opposite end portions and said clamping means having interengageable surfaces for tightening said engaging means about a container upon relative rotation between said clamping means and said opposite end portions, handle means defining a substantially uninterrupted outer surface which is presented to view when in operative position so as to afford a neat and attractive appearance with no attaching or connecting parts exposed to view, said handle means including a manually graspable portion and having a cavity therein disposed adjacent said

band and receiving said opposite end portions of the engaging means and said clamping means whereby said opposite end portions and said clamping means are completely hidden from view when in operative position, and means securing said opposite end portions and said clamping means fixedly within said cavity.

7. Apparatus as defined in claim 6 wherein said interengageable surfaces include cam means on said clamping means.

8. Apparatus as defined in claim 6 wherein said interengageable surfaces include interengageable screw thread portions, the terminal ends of said opposite end portions including ears extending laterally from the adjacent parts of the end portions, said ears overlapping and being interengageable with one another and serving to maintain said

opposite end portions in predetermined spaced relationship to one another.
